UNITED STATES PATENT OFFICE.

JOHN HOPE, OF GLASGOW, SCOTLAND.

STONE-CUTTING TOOL.

1,282,424.

Specification of Letters Patent. Patented Oct. 22, 1918.

Application filed May 14, 1918. Serial No. 234,478.

To all whom it may concern:

Be it known that I, JOHN HOPE, a subject of the King of the United Kingdom of Great Britain and Ireland, and residing at 5 Glasgow, Scotland, have invented a certain new and useful Improvement in Stone-Cutting Tools, of which the following is a specification.

This invention relates to improvements in 10 stone-cutting tools for cutting emery and other stones.

According to the invention, the journals for the cutting wheel or wheels have bearings in removable plugs fitted to vertically 15 disposed sockets in the tool head and adapted to be locked in position by means movable with a covering member adjustable relatively to the tool head.

The invention is illustrated in the accompanying drawings in which Figure 1 is a 20 plan of the complete tool, part of the cover being broken away. Fig. 2 is a side elevation and Fig. 3 an end elevation of the tool head. Fig. 4 is a section through the tool 25 parallel to the handle, and Fig. 5 is a cross section.

As shown the journals 4 of the cutters 5 are mounted in plugs 6 slidable into sockets in the tool head A which is formed with a 30 notch between the sockets to accommodate the cutters.

Extending from one socket to the other is a slot 7 so that the cutters, journals and plugs may be fitted into place simultaneously.

35

8 denotes an adjustable cover whose end-wise travel is limited by pins 9 entering slots 10 in the cover.

The cover 8 carries light rods or wires 40 11 movable in perforations in the tool head and engageable in transverse porforations or recesses in the plugs 6 so as to lock the plugs 6 in place.

What I claim is:—

In a stone-cutting tool, the combination 45 with a tool head having a notch, and provided with vertical sockets one on each side of the notch, plugs removably fitted to said sockets, a cutter accommodated in said notch with journals having bearings in said plugs, an 50 adjustable cover, and means carried by said cover serving to lock said plugs in position.

In testimony whereof I have signed my name to this specification in the presence of two subscribing witnesses.

JOHN HOPE.

Witnesses:

HENRY MASON,
ANNE R. WATT.
